MOUNTING FOR ARTICLES

George H. Leonard, Noroton Heights, Conn., assignor to Machlett Laboratories Incorporated, Springdale, Conn., a corporation of Connecticut

Application October 16, 1947, Serial No. 780,285

5 Claims. (Cl. 248—361)

1

This invention relates to mountings, in which objects of various kinds may be supported, and is concerned more particularly with a novel mounting, which holds the object securely but permits its easy insertion and removal. The new mounting is especially adapted for supporting electronic tubes and, in that application, the mounting may include means for cooling the anode structure of the tube. Such a form of the mounting also includes packing means for preventing escape of the cooling fluid along the tube and through the mounting, such means becoming effective automatically upon insertion of the tube in the mounting. As all of the advantages of the invention are utilized in a form of the new mounting for use with electronic power tubes and having anode cooling means, such an embodiment of the invention will be illustrated, and described in detail for purposes of explanation.

The preferred form of the mounting provided with anode cooling means includes a body having an opening, through which the anode section of the tube may be inserted. A chamber attached to the body provides an enclosure for the anode and cooling fluid may be circulated through the chamber around the anode. The body is provided with a circumferential seat within the opening and a resilient packing ring of toroidal form is mounted within the body upon the seat to encircle the opening. The ring extends into the path of a part of the anode section, as the latter is inserted through the opening and ring, and the ring is deformed by engagement with that part of the anode section to increase its area of contact with the seat. Tubes of the power type are frequently provided with a collar adjacent the inner end of the anode section and, in order to prevent withdrawal of the tube from the mounting, the body is provided with means, which are movable to overlie the collar or other part of the tube, when the tube is fully inserted in the mounting.

In one form of the new mounting, the circumferential seat within the body extends parallel to the axis of the opening and, in this construction, the effectiveness of the ring in making leak-proof contact with the body and the tube does not depend on axial clamping pressure applied to the ring through a part of the tube. In that form of the mounting, the means for holding the tube in place in the mounting is, accordingly, not utilized to apply pressure to deform the packing ring and merely engages the collar or other projecting part of the tube, so as to prevent the tube from being forced out of the mounting by

2

the pressure of the cooling fluid against the projected area of the anode end of the tube.

In another form of the mounting, the circumferential seat faces the end of the body, into which the anode end of the tube is introduced, and the desired leak-proof contact of the ring with the seat and tube is established by pressure applied axially through the collar to the ring by the means overlying the collar and preventing removal of the tube from the mounting. In still another construction, the insertion of the tube in the mounting causes deformation of the ring into increased contact with the seat and, when the cooling fluid under pressure is admitted into the chamber around the tube, the pressure may cause an outward movement of the tube and the ring, with the latter distorted into increased contact with the seat and tube by the pressure.

For a better understanding of the invention, reference may be made to the accompanying drawings, in which:

Fig. 1 is a longitudinal sectional view on the line 1—1 of Fig. 3 through one form of the new mounting;

Fig. 2 is a sectional view on the line 2—2 of Fig. 4, showing the mounting with a tube in place therein;

Figs. 3 and 4 are sectional views on the lines 3—3 of Fig. 1 and 4—4 of Fig. 2, respectively;

Fig. 5 is a fragmentary sectional view on the line 5—5 of Fig. 6 showing a modified construction;

Fig. 6 is a top plan view of the mounting of Fig. 5;

Fig. 7 is a fragmentary longitudinal sectional view showing another modified form of the mounting;

Fig. 8 is a view similar to Fig. 7, showing a tube in place in the mounting;

Fig. 9 is a sectional view on the line 9—9 of Fig. 7;

Figs. 10 and 11 are, respectively, fragmentary longitudinal sectional views of another modified form of the mounting with a tube in place therein and showing the parts in different positions;

Fig. 12 is a fragmentary longitudinal sectional view of another form of the mounting;

Fig. 13 is a view similar to Fig. 12 showing a tube in place in the mounting;

Fig. 14 is a fragmentary longitudinal sectional view showing another form of the mounting;

Fig. 15 is a view similar to Fig. 14 showing a tube in place in the mounting;

Figs. 16 and 17 are fragmentary sectional views of another modified form of the mounting with

a tube in place therein, the views showing the parts in different relations;

Fig. 18 is a fragmentary longitudinal sectional view of another form of the new mounting; and

Fig. 19 is a view similar to Fig. 18 showing a tube in place in the mounting.

The mounting shown in Figs. 1 and 2 is intended to be used with a power tube, which comprises an anode section 10 of generally cylindrical form. The tube has a collar 11 adjacent the inner end of the anode section and, beyond the collar, the tube includes a glass envelope 12 sealed to the enlarged inner end of the anode section.

One form of the new mounting for use with the tube described includes an annular body 13 having an internal flange 14, defining an opening of larger diameter than the anode section 10 of the tube but of less diameter than collar 11. A chamber 15 extends from one end of the body in position to receive the anode section of the tube, when the tube has been inserted in the mounting with its collar resting on the shoulder 14a formed on the outer surface of the flange 14. At the outer side of the flange the body is formed with an internal channel c, the bottom of which forms a circumferential seat 15a. A packing ring 16 lies within the channel in contact with the seat.

The packing ring is of resilient material, such as a suitable rubber or synthetic rubber compound, and it is of toroidal form. The ring ordinarily is of circular cross-section, but, in some applications, a ring that is square or triangular in cross-section may be employed. The bottom of the channel forms a circumferential seat against which the ring bears, and the ring projects inwardly into the opening through the body so as to lie in the path of a part of the anode section of the tube to be inserted in the mounting. In the construction shown, when the tube is being inserted in the mounting, the collar 11 engages the inner surface of the ring and causes the ring to be expanded and distorted, so as to increase its area of contact with the seat at the bottom of the channel. The width of the channel is greater than the greatest diameter of the ring, when so distorted, and ordinarily the ring does not make contact with the walls of the channel.

The end of the body opposite to that from which chamber 15 extends, is formed with an internal channel, in which is seated a split retainer ring 17. The ring is made of springy metal and, under normal conditions, it is seated tightly against the outer wall of the channel. The normal inner diameter of the retainer ring is sufficient to permit the passage therethrough of collar 11. The retainer ring is held in place by a cap plate 18 secured to the end of the body to overlie the ring by screws 19. A channel is formed in the face of the body along the outer edge of the latter beneath the cap plate and a locking ring 20 is mounted in this channel. The locking ring extends outwardly beyond the outer surface of the body and its exposed edge is knurled, as indicated at 21.

The inner edge of the locking ring is formed with a plurality of cam surfaces 22, and, opposite each cam surface, the top of the body is formed with a radial slot, in which lies a row of metal balls 23. The balls are in tight contact with one another and with the retainer ring 17 at one end of the row and with the cam surface 22 at the other end. At one end, each cam surface is provided with a notch 24, for a purpose

to be described. The locking ring may be moved angularly with respect to the body of the mounting and such angular movement is limited by a pin 25, which is mounted in an opening in the top of the body and has a projecting end lying within an arcuate notch 26 in the inner edge of the locking ring.

The closed end of chamber 15 is provided with a threaded opening for reception of a pipe 27, through which cooling fluid may be introduced into the chamber. The fluid flows upwardly between the chamber wall and the tube and leaves through an opening in the side of body 13, into which an outlet pipe 28 is threaded. Opposite the outlet opening, the body is formed with an internal channel 29 to permit an increased flow of the fluid around the tube to the outlet.

In the use of the mounting, the locking ring is first moved to the position illustrated in Fig. 3, in which the deep portion of each cam groove lies opposite the end of the row of balls associated with that groove. In that position of the locking ring, the retainer ring 17 is fully expanded. The anode end of the tube is then inserted into the mounting and, when the collar 11 enters the packing ring 16, it causes the latter to be distorted to make extended contact with the seat 15a at the bottom of the groove, in which the packing ring lies, and with the surface of the collar. The tightness of the contact of the packing ring with these surfaces does not depend on axial pressure applied to the tube but results from the pressure applied to the inner surface of the packing ring by the collar. After the tube is in position with the collar seated on flange 14, the locking ring 20 is moved angularly to cause the cam surfaces to act through balls 23 to collapse the retainer ring, so that it overlies the end of the collar 11. With the parts in the positions described, the tube is securely held in position and can only be withdrawn after the locking ring has been returned to the position illustrated in Fig. 3. When the locking ring has been moved to its extreme position for locking purposes, the outer balls in the rows enter the notches 24 at the ends of the cam surfaces and the seating of the balls in the notches prevents the locking ring from being shifted to open position by vibration. The tightness of the contact of the packing ring with the surfaces of its channel and with the surface of the collar is increased by the pressure of the fluid, which may escape around the inner edge of the flange 14 into contact with the packing ring.

In the modified locking construction shown in Figs. 5 and 6, the locking ring 20' is formed with an inwardly projecting arm 30, which lies in a cavity in the end of body 13 between stop surfaces 31, 32, and extends into the space between the ends of the retainer ring 17. When the locking ring 20' is moved to locking position, the inner end of arm 30 lies close to the ends of the retainer ring, so that, if the retainer ring should be corroded and adhere to the collar of the tube, the movement of the locking ring in clockwise direction to release the tube would cause the end of arm 30 to engage one end of the retainer ring 17 and break the adhesion of the ring to the tube.

In the modified construction shown in Figs. 7 to 9, inclusive, the body 33 of the mounting is formed with an inner wall 34 forming a circumferential seat, at the inner end of which is a flange 35. The body is formed with a plurality of radial openings, in which are mounted pins

38, each of which has a groove on the under side of its end exposed beyond the body. A ring 37 encircles the body and is supported on a ring 38 seated in a circumferential recess in the outer surface of the body and projecting beyond that surface. Ring 37 is provided with a plurality of cams 39, which enter grooves in the respective pins 36.

A packing ring 40 is mounted within the body against the seat 34 and the ring is of less internal diameter than the cylindrical portion 41 of the anode section of the tube. When the anode section is inserted through the body and ring, the ring is distorted to increase its area of contact with the seat 34 and also with the inner surface 42 of flange 35. When the collar 43 on the tube has passed inward beyond the pins 36, ring 37 may be moved angularly and the cams thereon then move the pins 36 inwardly to overlie the collar. The tube is then held against withdrawal and the distortion of the packing ring into increased contact with seat 34 and the inner surface 42 of flange 35 by engagement of the anode section with the inner surface of the ring insures a leakproof connection.

The construction shown in Figs. 10 and 11 is somewhat similar to that shown in Fig. 7, except that the tube is formed with a collar 44 having a beveled section 45. As the tube is moved into the mounting, the packing ring 46 is engaged from within by the beveled section 45 of the collar and forced into increased contact with the circumferential seat 41 on the inner surface of the body and also with the inner surface of flange 48 extending transverse to the axis of the opening through the body.

In the construction shown in Figs. 12 and 13, the body is formed with an internal flange 49, one face 49a of which forms a circumferential seat encircling the opening through which the anode end 50 of the tube is to be inserted. A packing ring 51 rests upon seat 49a and the ring has an internal diameter, which may be greater than the diameter of the anode section 50 but is less than the outer diameter of the collar 52 of the tube. The outer surface of the tube is provided with threads 53, with which are engaged the threads in the interior of a nut 54. The nut is formed with a recess inward from the threads, and a ring with a cam surface 56 is mounted in the recess. A split retainer ring 57 having a beveled surface engaging the cam surface 56 on ring 55 is also mounted in the recess. With the construction described, the tube is inserted in the mounting until the collar rests upon the top of the packing ring 51 and the top of the collar lies beneath the lower edge of the retainer ring 57. Nut 54 is now turned until the cam ring 55 moves down to engage the end of the body, after which further turning of the nut causes the locking ring to be forced inwardly along the cam surface 56. The retainer ring initially moves inwardly to overlie the upper end of collar 52 and thereafter acts through the collar to move the tube inwardly into the mounting, so that the collar deforms the packing ring 51 to give it increased areas of contact with seat 49a and the under surface of collar 52.

The construction shown in Figs. 14 and 15 is employed with a tube, the anode section 58 of which has a re-entrant portion at the outer end of which is mounted a ring 59. The body 60 of the mounting has an opening with an internal circumferential recess, the bottom of which forms a seat 61 against which a packing ring 62 of 75

toroidal form may be seated. The packing ring also makes contact with the inclined end surface 63 of a ring 64, which lies within the opening through the body and rests upon a spring 65 bearing against a flange 66 at one end of the body. The wall 67 of the cooling chamber extends through the mounting and terminates at 68 within the re-entrant portion of a tube in the mounting. A collapsible retainer ring 69 is mounted at the end of the body and is held in place by a cap plate 70. A locking ring 71 is mounted in the outer wall of the tube and has cam recesses, in each of which is mounted a ball 72 engaging the outer surface of the retainer ring, the arrangement being generally similar to that shown in Fig. 3.

Upon insertion of tube 58 in the mounting shown in Figs. 14, 15, the collar 59 on the anode section of the tube makes contact with the packing ring 62 and, as the tube is moved inwardly into the mounting, the packing ring is distorted into increased contact with the seat 61 and the sloping surface 63 of ring 64, which forms a second seat for the ring. When the tube has been moved sufficiently far into the mounting, ring 71 is moved angularly and balls 72 are cammed inwardly to collapse the retaining ring 69, until it overlies the outer surface of collar 59. The pressure of the cooling fluid, which may be introduced into the chamber enclosing the anode end of the tube in any convenient manner, as, for example, through an opening 73 in flange 66 on the body, insures that the packing ring will make tight contact with a seat 61 and with the inner end of collar 59.

In the constructions shown in Figs. 16 and 17, the body 74 of the mounting is formed with an internal flange 75 and a packing ring 76 normally rests upon the face of the flange and against a seat 77 formed by the inner surface of the body. The tube has an anode section 78 of less diameter than the internal diameter of ring 76 and it is also provided with a collar 79, which is of only slightly less diameter than the outer diameter of the ring. The body is provided with locking means, which are illustrated as pins 80, which may be independently operated or operated simultaneously by means of a locking ring, such as the locking ring 71 and balls 72, shown in Fig. 14. When a tube is to be placed in the mounting of Fig. 16, its anode end is passed through the opening in the body until the collar 79 on the tube rests upon the packing ring 76. The retaining pins 80 are then moved inwardly to overlie the upper surface of the collar. The mounting is provided with a cooling chamber (not shown) through which cooling fluid under pressure is circulated and, when the tube is in place in the mounting and the fluid admitted to the chamber, the pressure of the fluid against the end of the anode section of the tube moves the tube outwardly until collar 79 engages pins 80. At the same time, the pressure of the fluid forces the locking ring into increased contact with the seat 77 and the inner surface of collar 79.

In the construction shown in Figs. 18 and 19, the body 81 of the mounting is formed with an internal flange 82 somewhat inclined to the axis of the opening through the body and formed with a plurality of openings 83. A packing ring 84 is mounted within the body to rest on the outer surface of flange 82 and the body is provided with retaining means in the form of radial pins 85. When the tube is inserted in the mounting,

the anode section 86 of the tube is passed through the opening defined by flange 82, until the collar 87 on the anode section engages the packing ring 84 and distorts it into contact with the inner wall 88 of the body and into increased contact with flange 82. The pins 85 are then moved inwardly to overlie the outer face of the collar and the tube is then firmly held in place. The mounting is provided with a cooling chamber (not shown) receiving the anode section of the tube and, when cooling fluid under pressure is admitted into the chamber, it flows through the opening 83 in the flange and also around the inner edge of the flange to apply pressure to packing ring 84 and insure a leak-proof contact of the ring with the circumferential seat 88 in the body and the inner surface of collar 87.

Although a number of different forms of locking means for retaining the tube in the mounting have been shown, the constructions including a retaining ring and illustrated in Figs. 3, 6, and 14 are preferred for the following reasons. When the retainer ring 17, in the construction shown in Figs. 1-5, inclusive, for example, has been collapsed to overlie a part of the tube, such as the collar 11, and water has been admitted to the jacket, the pressure of the water against the tube causes collar 11 to clamp the retainer ring 17 tightly against the under-surface of the cap plate 18. At this time, the outermost balls 23 in each row lie in their notches 24 in the locking ring 20 and, in order to release the retainer ring, the locking ring must be turned clockwise (as shown in Fig. 3). In the initial part of such movement of the locking ring, the balls are forced inwardly to permit the outermost ball in each row to move out of its notch 24, and such inward movement of the balls causes a slight further collapse of the retainer ring. However, when the water pressure is applied to the tube, the collar 11 clamps the retainer ring 17 so tightly against the under-side of the cap plate 18 that the locking ring can not be turned by hand. As a result, it is impossible to move the retainer ring to inoperative position while the water pressure is on and thus there is no possibility of discharge of water and accidental forceful expulsion of the tube from the mounting is prevented.

If, as a result of carelessness in locking the tube in the mounting, the locking ring is not moved until the outermost ball in each row is in its notch 24 and thereafter the water is turned on, it might be possible by application of considerable force to move the locking ring to release the retainer ring. However, the pressure of the water would cause the retainer ring to be clamped against the cap plate so tightly that the retainer ring could not expand and release the tube from its mounting.

Another advantage of using the retainer ring construction for holding the tube in its mounting is that the retainer ring makes a flat and substantially continuous contact throughout the entire circumference of the collar 11 or a like part of the tube, when the tube is locked in the mounting. The pressure of the water against the tube is thus resisted throughout practically the entire circumference of collar 11 and no points of stress develop on the collar with resultant possible distortion of the latter. Even a slight distortion of the collar may produce stresses, which are transmitted to the seal between the anode section and the glass envelope 12, and such stresses may result in leakage at

the seal. With the construction described, the pressure applied to collar 11 is approximately that of the internal water pressure only and, because of the distribution of that pressure continuously throughout substantially the circumference of the collar, the application of the water pressure to the tube is not transmitted through localized areas of the collar to the metal-to-glass seal with resultant damage thereto.

I claim:

1. A mounting for an article having an outwardly projecting circumferential collar spaced inwardly from one end of the article, which comprises an annular body, a circumferential shoulder extending inwardly from the wall of the body in an opening through the body, the opening having an inner diameter larger than the outer diameter of the collar and the shoulder having an inner diameter greater than the outer diameter of said end of the article and less than that of the collar, an internal circumferential channel in the wall of the opening in the body between the shoulder and the outer end of the body, the bottom of the channel forming a circumferential seat, a resilient packing ring of toroidal form lying partially within the channel against the seat, the ring having a thickness less than the width of the seat and an internal diameter greater than the outer diameter of said end of the article and less than that of the collar, a resilient retainer ring mounted at the outer end of the body to surround the opening through the body, the ring being collapsible to overlie the collar of an article in the mounting, a locking ring mounted on the body for angular movement and encircling the retainer ring, and cam means operable by movement of the locking ring to collapse the retainer ring, the collar lying within the packing ring, when the collar is between the shoulder and the retainer ring.

2. A mounting for an article having an outwardly projecting circumferential collar spaced inwardly from one end of the article, which comprises an annular body, a circumferential shoulder extending inwardly from the wall of the body in an opening through the body, the opening having an inner diameter larger than the outer diameter of the collar and the shoulder having an inner diameter greater than the outer diameter of said end of the article and less than that of the collar, an internal circumferential channel in the wall of the opening in the body between the shoulder and the outer end of the body, the bottom of the channel forming a circumferential seat, a resilient packing ring of toroidal form lying partially within the channel against the seat, the ring having a thickness less than the width of the seat and an internal diameter greater than the outer diameter of said end of the article and less than that of the collar, a resilient split retainer ring mounted at the outer end of the body to surround the opening through the body, the ring being collapsible to overlie the collar of an article in the mounting, a locking ring mounted on the body for angular movement and encircling the retainer ring, means on the body for limiting the movement of the locking ring and the angular displacement of the retainer ring, and cam means operable by movement of the locking ring to collapse the retainer ring, the collar lying within the packing ring, when the collar is between the shoulder and the retainer ring.

3. A mounting for an article having an outwardly projecting circumferential collar spaced

inwardly from one end of the article, which comprises an annular body, a circumferential shoulder extending inwardly from the wall of the body in an opening through the body, the opening having an inner diameter larger than the outer diameter of the collar and the shoulder having an inner diameter greater than the outer diameter of said end of the article and less than that of the collar, an internal circumferential channel in the wall of the opening in the body between the shoulder and the outer end of the body, the bottom of the channel forming a circumferential seat, a resilient packing ring of toroidal form lying partially within the channel against the seat, the ring having a thickness less than the width of the seat and an internal diameter greater than the outer diameter of said end of the article and less than that of the collar, a resilient split retainer ring mounted at the outer end of the body to surround the opening through the body, the ring being collapsible to overlie the collar of an article in the mounting, a locking ring mounted on the body for angular movement and encircling the retainer ring, the locking ring having a projection lying between the ends of the retainer ring, and cam means operable by movement of the locking ring to collapse the retainer ring, the collar lying within the packing ring, when the collar is between the shoulder and the retainer ring.

4. A mounting for an article having an outwardly projecting circumferential collar spaced inwardly from one end of the article, which mounting comprises an annular body having an inner diameter larger than the outer diameter of the collar, a circumferential shoulder extending inwardly from the wall of the body in the opening through the body, said shoulder having an inner diameter greater than the outer diameter of said end of the article and less than that of the collar, an internal circumferential channel in the wall of the opening in the body between the shoulder and the outer end of the body, the bottom of the channel forming a circumferential seat, a resilient packing ring of toroidal form lying partially within the channel against the seat, the ring having an internal diameter greater than the outer diameter of said end of the article and less than that of the collar and a thickness less than the width of the seat which thickness is of the same order of magnitude as the axial length of the collar, and means at the outer end of the body for preventing removal of the article from the body, said means including an element movable radially to overlie the collar of the article, the collar lying within the packing ring, when the collar is between the shoulder and

the movable element, the packing ring forming a fluid-tight seal between the circumferential seat and the collar, the means for preventing removal of the article from the body being independent of the means for making said fluid-tight seal.

5. A mounting for an article having an outwardly projecting circumferential collar spaced inwardly from one end of the article, which mounting comprises an annular body having an inner diameter larger than the outer diameter of the collar, a circumferential shoulder extending inwardly from the wall of the body in the opening through the body, said shoulder having an inner diameter greater than the outer diameter of said end of the article and less than that of the collar, an internal circumferential channel in the wall of the opening in the body between the shoulder and the outer end of the body, the bottom of the channel forming a circumferential seat, a resilient packing ring of toroidal form lying partially within the channel against the seat, the ring having an internal diameter greater than the outer diameter of the said end of the article and less than that of the collar and a thickness less than the width of the seat, which thickness is of the same order of magnitude as the axial length of the collar, means for preventing removal of the article from the body including a resilient retainer ring 10 mounted at the outer end of the body to surround the opening through the body and collapsible to overlie the collar of an article in the mounting, and cam means for collapsing the retainer ring, the collar lying within the packing ring, when 15 the collar is between the shoulder and the movable element, the packing ring forming a fluid-tight seal between the circumferential seat and the collar, the means for preventing removal of the article from the body being independent of 20 the means for making said fluid-tight seal.
